ENGINE CYLINDER BLOCK

Fred G. Shoemaker, Ferndale, and Gunnar E. Ehrling, Detroit, Mich., assignors, by me and assignments, to General Motors Corporation, Detroit, Mich., a corporation of Delaware

Application April 5, 1933, Serial No. 664,505

10 Claims. (Cl. 123—173)

This invention relates to built up engine cylinder blocks consisting of parts which can be simply and cheaply produced and assembled and supported upon each other preferably by press fits so as to be self holding in one complete assembly adapted to be soldered, welded, or brazed into a single whole.

More particularly, it relates to such cylinder blocks for engines having ports in their cylinder walls for the flow of fluid into or out from the cylinder, and still more particularly to a U-type two-cycle internal combustion engine.

Each cylinder is as far as possible a complete unit in itself adapted for combining into a single or multi-cylinder block of any desired number of cylinders with the use of only a few additional parts such as suitable top and bottom plates or deck flanges connecting any required number of cylinders together.

One object of the invention is the construction of engine cylinder blocks of the foregoing type having known advantages of lightness in weight and ability to provide for a greater rate of extraction or dissipation of the waste heat of the engine cycle, in which the port conduits through the cylinder walls and a surrounding water jacket are formed wholly by and in the cylinder barrel and the water jacket by suitable machining thereof.

Another object of the invention is to reduce the resistance of the walls between the port conduits to the flow of fluid through the port conduits by the provision of streamline fairing pieces therefor.

Another object of the invention is suitable provision for cooling the streamline fairing pieces which are exposed to the hot exhaust gases and which form part of a port chamber which is itself water cooled and encloses the port conduits.

A further object of the invention is to provide water inlet means for the water jacket of each cylinder at diametrically opposite sides thereof through the lower hold down flange of the cylinder block.

A still further object of the invention is to construct a ribbed upper or top deck flange for a cylinder block which, while thin and capable of being efficiently cooled, is adequately strong.

The above and other objects of the invention are hereinafter described in conjunction with the accompanying drawings which show the application of the invention to the two complementary cylinders having a common combustion chamber of a U-type two-cycle internal combustion engine in which the cylinders are united by

a suitable upper deck flange to which the cylinder head is attached and a lower hold down flange, are provided with separate water jackets for each cylinder barrel, are provided with water cooled ports with streamline fairing pieces to lead the gases through the ports and have port chambers enclosing the fairing pieces through which the gases are led into or out from the ports.

In the drawings:

Figure 1 is a sectional elevation of the two complementary cylinders complete with cylinder head. 10

Figure 2 is a section on line 2—2 of Figure 1. 15

Figure 3 is a perspective view of the underside of the upper or top deck flange.

Figure 4 is a perspective view of the upper end of a cylinder barrel. 15

Figure 5 is an exploded perspective view of the intake port chamber.

Figure 6 is a perspective view of the intake port 20 fairing pieces.

Figure 7 is a perspective view of the exhaust port chamber with tubular fairings for the cylinder port conduits.

Figure 8 is an elevation of the exhaust port 25 chamber water jacket.

Figure 9 is a part sectional, part end elevation of the cylinder block showing the lower end of a cylinder barrel complete with the lower hold down flange, the water jacket, and water inlet 30 connections therefor.

The two cylinder barrels 1 and 2 which may be termed inlet and exhaust cylinders respectively are machined from steel tubing.

The outer circumference of the inlet cylinder 35 barrel 1 is turned with a shoulder 3, a thin flange 5, a thicker section 7 and a shoulder 9. The exhaust cylinder barrel is turned correspondingly with a shoulder 4, a thin flange 6, a thicker section 8 and a shoulder 10. All other unnecessary 40 material on the outer circumference of the cylinder barrels is machined away leaving strengthening ribs 11.

The thicker sections 7 and 8 forming integral sleeve portions constitute the necessary stock in 45 which to form the port conduits 13 and 14 for the cylinder barrels 1 and 2 respectively. These thicker sections 7 and 8 partition the annular space between each cylinder barrel and its surrounding water jacket. Between the port conduits 13 of the inlet cylinder barrel 1 grooves 15 are milled in the thicker section sleeve portion 7 to constitute cooling spaces for the cylinder walls between the ports and for the port conduits, and to serve as ducts for the flow of water from 50 55

one side to the other of the partitioned cooling space. Similar grooves 16 are milled in the sleeve portion 8 of the exhaust cylinder barrel 2.

The inlet port conduits 13 are milled directionally tangential to, and converging towards the median circumference of the inlet cylinder bore as shown in Figure 2 so as to give rotational flow of the incoming charge of fluid in a plane at right angles to the cylinder axis, in a clockwise direction as seen in Figure 2.

The exhaust port conduits 14 are milled directionally as shown in Figure 2 to give easy egress of the exhaust gases in the cutlet direction.

The thin flanges 5 and 6 are notched out as shown in Figure 4 to provide passageways for the flow of water as will be later described.

The forged hold down flange 17 common to the two cylinders and provided with bolt holes such as 18 is slipped over the lower ends of the two cylinder barrels and pressed up against the shoulders 9 and 10 on the cylinder barrels 1 and 2 respectively. Circumferential shoulders 19 and 20 are provided on the hold down flange 17.

The water jackets 20 and 21 for the cylinder barrels 1 and 2 are made from steel tubing machined inside and out. These water jackets which are provided with port openings 22 and 23 coincidental with the openings of the port conduits 13 and 14 on the outer circumference of the cylinder barrels are press fitted over the sleeve portions 7 and 8 and the flanges 5 and 6.

The inlet port chamber 24 is formed of two lap jointed halves 25 and 26 consisting of sheet steel stampings as shown in Figure 5. This port chamber is press fitted over the inlet cylinder water jacket 20.

Inserted in the port chamber are two segments 27 and 28 of a ring having ports 29 to coincide with the cylinder port conduits and having a conformation such as to provide fairings for those parts of the cylinder wall or the water jacket surrounding and between the port conduits enclosed by the port chamber for the smooth streamline directional flow of the charge 45 through the port chamber into the port conduits. These port fairing pieces are conveniently formed of cast aluminum and are held in their proper position in the inlet port chamber by any suitable means. They may be pinned through the port chamber.

The exhaust port chamber 30 is similarly formed of two lap jointed halves 31 and 32 with punched holes 33 in each half connected by tubular fairing pieces 34. These fairing pieces are subjected to the heat of the hot exhaust gases, hence the need for water cooling of the fairing pieces. The tubular fairing pieces 34 are press fitted over the vertical sides of the punched holes 33 which form a plug and socket joint with the tubular fairing pieces.

A water jacket 34' for the exhaust port chamber 30 is similarly formed of two lap jointed halves enclosing the exhaust port chamber. Both the exhaust port chamber and the water jacket 65 are press fitted over the exhaust cylinder water jacket 21.

Holes 40 in the cylinder water jacket 21 above and below the exhaust port chamber 30 serve as inlet and outlet ports for the flow of water between the water space around the cylinder barrel and the water space around the port chamber.

The inlet port chamber 24 is slipped over the inlet cylinder water jacket 20 and located in its proper position against a shoulder 35 thereon.

The exhaust port chamber 30 along with its

water jacket 34' is slipped over the exhaust cylinder water jacket 21 and located in its proper position against a shoulder 36 thereon.

The water jackets complete with their port chambers are next slipped down over the flanges 5 and 6, the sleeve portions 7 and 8, and onto the shoulders 19 and 20 on the hold down flange 17.

A water jacket extension piece 37 is next slipped over the upper end of the water jackets 10 20 and 21 and against shoulders 38 and 39 thereon. This water jacket extension piece forms the top closure of the water jacket between the cylinder water jackets and the upper deck flange 41, the water flowing through ports formed by 15 notches in the thin flanges 5 and 6 as shown most clearly in Figure 4.

The upper deck flange is press fitted in the water jacket extension piece 37 and over the cylinder barrels 1 and 2, and is pressed into position against the shoulders 3 and 4 of the cylinder barrels.

Flanges 42 and 43 are press fitted over the open ends of the inlet port chamber 24 and the exhaust port chamber 30 with its water jacket 25 36'.

The hold down flange 17 is provided with stepped down portions 44 along the sides of the cylinder block at diametrically opposite points of each cylinder barrel. Holes 45 are provided in 30 this stepped down portion of the hold down flange. Water inlet port openings 46 are provided in the cylinder water jacket above the holes 45.

Tubular water inlet conduits 47 carry the cooling water through the holes 45 in flange 17 and through the port openings 46 into the water jackets. The inlet conduits 47 are press fitted in the holes 45.

By arranging the water inlet conduits through the hold down flange in the foregoing manner, the joint between the cylinder block hold down flange and the crank case (not shown) may serve also as the joint between the water inlet conduits and a common rail water supply line (not 45 shown) which may be formed in the crank case.

As shown in Figure 3 the underside of the upper deck flange 41, a steel forging, is provided with pockets 48 between the tapped stud holes 49 into which the studs for the removable cylinder head are screwed. The bridge portion between the two cylinder barrels is provided with strengthening ribs 50 and 51. All the spaces and pockets on the underside of the flange function as water cooling spaces while at the same time 55 they lighten the weight of the flange. Holes 52 in the bridge portion and in each pocket 48 serve for the flow of water from the water jackets of the cylinder barrels into the water jacket of the cylinder head 53 which is provided with 60 coincidental holes and has a water outlet 54.

We claim:

1. In a built up internal combustion engine cylinder block a cylinder barrel, a top deck flange forming part of a combustion chamber, a water jacket for the cylinder barrel, a closure for the water jacket at the combustion chamber end of the cylinder barrel consisting of a flange on the cylinder barrel, and ports in the flange for the flow of water from the water jacket of the cylinder barrel into a water jacket extension piece connecting the water jacket of the cylinder barrel to the top deck flange and constituting a cooling jacket for that part of the top deck flange forming part of the combustion chamber.

2. In a built up engine cylinder block in combination, a cylinder barrel, a top deck flange for the cylinder head end and a hold down flange for the other end of the cylinder barrel, a water jacket for the cylinder barrel, a flange on the cylinder barrel forming a closure for the water jacket at the cylinder head end, a water jacket extension piece connecting the water jacket of the cylinder barrel to the top deck flange and forming a water jacket therefor, ports through the second named flange for the flow of water from the water jacket of the cylinder barrel to the water jacket of the top deck flange, and port conduits through the walls of the cylinder for the flow of fluid into or out of the cylinder. 5
3. In a built up engine cylinder block in combination, a cylinder barrel, a top deck flange for the cylinder head end and a hold down flange for the other end of the cylinder barrel, a water jacket for the cylinder barrel, a flange on the cylinder barrel forming a closure for the water jacket at the cylinder head end, a water jacket extension piece connecting the water jacket of the cylinder barrel to the top deck flange and forming a water jacket therefor, ports through the second named flange for the flow of water from the water jacket of the cylinder barrel to the water jacket of the top deck flange, port conduits through the walls of the cylinder for the flow of fluid into or out of the cylinder, and a port chamber enclosing the port conduits and adapted to secure the streamline directional flow of fluid into or out of the port conduits. 10
4. In a built up engine cylinder block in combination, a cylinder barrel, a top deck flange for the cylinder head end and a hold down flange for the other end of the cylinder barrel, a water jacket for the cylinder barrel, a flange on the cylinder barrel forming a closure for the water jacket at the cylinder head end, a water jacket extension piece connecting the water jacket of the cylinder barrel to the top deck flange and forming a water jacket therefor, ports through the third named flange for the flow of water from the water jacket of the cylinder barrel to the water jacket of the top deck flange, port conduits through the walls of the cylinder for the flow of fluid into or out of the cylinder, a port chamber enclosing the port conduits and adapted to secure the streamline directional flow of fluid into or out of the port conduits, and a water inlet conduit for the water jacket of the cylinder barrel through the hold down flange. 15
5. In a built up engine cylinder block in combination, a cylinder barrel, a water jacket for the cylinder, forming cooling space therearound, a section of the cylinder barrel forming, together with a section of the water jacket, a partition for the cooling space, port conduits through the partition, for the flow of fluid into or out of the cylinder, channels in the partition between the port conduits and closed by the water jacket, forming cooling spaces for the cylinder barrel and the walls of the port conduits and providing for the flow of the cooling medium therethrough from the cooling space on one side of the parti- 20
- tion to the cooling space on the other side of the partition, and means providing for the directional flow of fluid with a minimum resistance to the flow thereof into or out of the port conduits consisting of a port chamber enclosing the port conduits and including fairings for those parts of the cylinder wall and the water jacket surrounding and between the port conduits enclosed by the port chamber. 25
6. A built up engine cylinder block according to claim 5 in which fairings for those parts of the cylinder walls surrounding and between the port conduits enclosed by the port chamber are formed in a fairing piece inserted and suitably held in the port chamber. 10
7. A built up engine cylinder block according to claim 5 in which the port chamber is provided with a water jacket which takes in water from the cylinder water jacket through holes therein above and below the port chamber and in which the fairings include separate pieces of tubular section which are cooled by themselves forming conduits for the flow of water through the port chamber from the lower to the upper side of the water jacket of the port chamber. 15
8. In a built up engine cylinder block in combination a cylinder, a water jacket for the cylinder, a hold down flange on the cylinder block and a water inlet conduit for the water jacket through the hold down flange. 20
9. In a built up internal combustion engine cylinder block, complementary cylinder barrels having a common combustion chamber, a top deck flange uniting the cylinder barrels and forming part of the combustion chamber, separate water jackets for each cylinder barrel, a lower closure for the water jackets consisting of a lower hold down flange common to the cylinder barrels and an upper closure for each water jacket consisting of a flange on each cylinder barrel provided with ports for the flow of water from the water jacket of each cylinder barrel into a water jacket extension piece common to the cylinder barrels connecting the water jackets of the cylinder barrels to the top deck flange and constituting a cooling jacket for that part of the top deck flange forming part of the combustion chamber. 25
10. In a built up internal combustion engine cylinder block, complementary cylinder barrels having a common combustion chamber, a cylinder head, a water jacket for the cylinder head, an upper deck flange uniting the cylinder barrels having a bridge portion forming part of the combustion chamber between complementary cylinder barrels, the upper deck flange having a thickness sufficient to provide adequate stock for tapped stud holes, pockets forming water cooling spaces between the stock for each stud hole, strengthening ribs in the water cooling space of the bridge portion and holes in the pockets for the flow of water therethrough into the water jacket of the cylinder head. 30
